UNITED STATES PATENT OFFICE.

GEORGE S. TIFFANY, OF SUMMIT, NEW JERSEY.

TELAUTOGRAPH.

Application filed July 14, 1920. Serial No. 396,290.

To all whom it may concern:

Be it known that I, GEORGE S. TIFFANY, a citizen of the United States, residing at Summit, county of Union, and State of New Jersey, have invented certain new and useful Improvements in Telautographs, fully described and represented in the following specification and the accompanying drawings, forming a part of the same.

10 This invention relates to a so-called automatic exchange for telautograph systems.

It is the object of the present invention to provide such an exchange including switching mechanism manually controlled from the several stations of the telautograph system whereby the transmitter of any one of the stations may be connected with the receiver of any of the other stations.

20 The exchange provided is also equipped with means whereby the operator of any station calling another which is "busy" at the time is notified of the fact, such notice being given without any disturbance in any of the other lines.

25 It is also equipped with means whereby while a station is calling or selecting another telautographic transmission is impossible and while it is transmitting, calling or selecting is impossible.

30 It is also so constructed and arranged that on the first movement of the manually controlling means at a calling or selecting station the switch mechanism therefor at the exchange is re-set or restored to normal position so that upon the further operation of such manually controlling means such switch mechanism will be properly actuated to select the desired station.

35 It is also equipped with additional means, at each station, operable on the termination of telautographic communication from one station to another, for so re-setting or restoring the switch mechanism, and means indicating to the operator that this re-setting or restoring operation has been performed.

40 It is also equipped with means, at each station, for indicating to the operator thereof when he has neglected to put his station into receiving condition, that is, has forgotten to throw the transmitter switch to receiving position.

45 All of these different means will be described in detail in connection with the accompanying drawings, in which—

Figures 1, 3 and 4 are diagrammatic views

illustrating three telautograph stations, each equipped with a manually-operated calling or selector switch, and

50 Figure 2 is a diagrammatic view of a central switching station equipped with three groups of step-by-step electrically-operated station-selecting switch mechanisms controlled by the manually operated selecting switches of the three stations, respectively, 55 so that each of the stations is capable of connection with either of the other two.

55 The three stations 1, 2, 3 of Figures 1, 3, 4 are alike, as to mechanism and circuits, so that a description of station 1, for example, will suffice for all, corresponding references being applied to Figures 3 and 4 followed, for convenience of description, by the letters "a" and "b" respectively.

60 Station 1 is provided with the usual battery A, (the neutral of which is connected with ground at 4 by wires 5, 6, 7) for supplying the line or writing currents, a transmitter B, a receiver C, and a master switch mechanism D. Transmitter B is equipped 65 with the usual rheostats 8, 9 and pencil-carrying arms 10, 11 having roller contacts bearing against the rheostats. Rheostats 8, 9 are connected, each at one end, by wires 12, 13, 14, 7 with ground at 4, and at their 70 opposite ends by wires 15, 16, 17, contact plate 18 and contact lever 19 of master switch D, wires 20, contact 21, armature 22 of a relay E and wire 23 with the positive 75 of battery A. Right hand pencil arm 10 is connected, by wires 24, 25, contact 26 and 80 contact plate 27 of master switch D, wire 28, winding of a relay F and wires 29, 30, with the right hand side of the local receiver C, and (from wire 28) by wire 31 85 and through the selector switch mechanism of Figure 2, with the right hand side of the receiver of the station 2 or 3, as the case may be. Left hand pencil arm 11 is connected, by wire 32, contact plates 33, 34 of 90 master switch D, and wires 35, 36 with the left hand side of the local receiver C, and (from wire 35) by wire 37, winding of a 95 relay G, wire 38, stationary contact 39, contact 40 on the lower end of a break arm 41 100 of insulating material (later on described) and wire 42 and through the switch mechanism of Figure 2, with the left hand side 105 of the receiver of the station 2 or 3, as the case may be. The complete right and main line circuits through the switch mechanism

110 to the distant receivers will be described

later on, as will also be the functions of the relays referred to.

All of these parts, with the exception of certain parts (including relays 27, 35, 45 and arm 49 and connections) later on described in detail, are well known in telautographic apparatus so that further description of them is unnecessary beyond stating that as the pencil arms 10, 11 are moved laterally in writing and their roller contacts therefore travel back and forth along the rheostats 8, 9, the strength of the currents traversing the right and left writing lines therefrom to the local and distant receivers varies, with the result that the receiving pens of these two receivers are caused to reproduce the movements of, and therefore the writing produced by, the transmitting pencil or tracer 43.

20 The means, before referred to, under the control of the operator, at station 1, for example, whereby the transmitter thereof may be connected with the receiver of any of the other stations, include manually operated calling mechanism (Figure 1) designated as a whole by the reference H, a group of step-by-step electrical and mechanical devices (Figure 2) arranged vertically one above the other, designated as a whole by the reference 100, (those for stations 2 and 3 being designated 200, 300 respectively) circuits for effecting the operation of said devices, and circuits for controlling them and which are in turn controlled by the manually operated selector mechanism H, as will now be described.

The manually operated calling selector or switch mechanism of Figure 1 includes a suitably journalled toothed wheel 44, fixed to a suitably journalled bearing pin 45, a pawl 46 for moving the wheel in a counter-clockwise direction and a retaining pawl 47 preventing its retrograde or clockwise movement. Pawl 46 is pivotally mounted in an arm 48 and is spring pressed into engagement with the toothed wheel 44, as is also the pawl 47. Arm 48 is fixed to a sleeve 49 loose on pin 45 so that the arm may be moved by hand in a clockwise direction carrying with it the pawl 46 and then be moved in a counter clockwise direction by a spring 50 so that said pawl will rotate the wheel 44 one, two or three teeth, according to the extent of the clockwise movement of the arm 48 with relation to the indications "1", "2", "3" above it. The speed of rotation of wheel 44, on the counter clockwise movement of arm 48 is governed by a worm gear 51 fixed to wheel 44 and engaging a worm 52 upon a suitably supported shaft 53 carrying a fan 54 at its lower end. The break arm 41 before referred to is frictionally clamped to sleeve 49 so as to move therewith and with arm 48. It carries at its lower end the contact 40 before referred to,

which is adapted to alternately engage the contact 39 and another contact 55. The pawl 47 also has a tail piece 56 which, each time the pawl is tripped on the counter-clockwise movement of wheel 44, engages a contact 57. The counter-clockwise movement of arm 48 and wheel 44 under the pull of spring 50 is limited by a stop 58.

It will be understood from the foregoing that as arm 49 is moved by hand in a clockwise direction from the position shown in Figure 1, arm 41, moving therewith, will be moved out of engagement with contact 39 and into engagement with contact 55, and that when the arm 49 is released it will be moved by spring 50 in a counter-clockwise direction, the wheel 44 being then rotated by the pawl 46 in the same direction. As the wheel is thus rotated its teeth will trip the pawl 47 and cause the contact tail piece 56 thereof to engage contact 57 each time the pawl is so tripped; the pawl 46, engaging the stop 58, being arrested thereby at the end of its counter-clockwise movement. Arm 41, rocked by the arm 49, will disengage its contact 40 from contact 55 and engage it with contact 39, as shown in Figure 1.

Through these movements of arm 41 and wheel 44 the operation of group 100 of the selector switch mechanism of Figure 2 is effected to connect the transmitter of station 1 with the receiver of station 2 or 3, according as the arm 41 is moved to "2" or "3" on the indicator above it, as will now be described.

The electrically operated switch mechanism 100 for station 1 comprises a ratchet wheel 101 having fixed to it an arm 102 of insulating material provided with a contact sector 103 adapted to engage a spring contact 104 when the arm 102 is moved by the clockwise rotation of ratchet wheel 101 from the position in which it is shown. A spring 105 tends to move the arm 102 and ratchet wheel 101 in the opposite direction or to normal position. Arm 102 is provided with contacts 106, 107, 108 connected respectively by wires 109, 110, 111 with stationary contacts 112, 113, 114, to which latter are connected wires 115, 116, 117 respectively constituting parts of circuits which will later on be described in detail. Contacts 106, 107, 108 of the arm 102, when the latter is moved clockwise on the rotation of ratchet wheel 101, are adapted to engage the set of contacts 112, 113, 114, a second set of contacts 118, 119, 120, or a third set of contacts 121, 122, 123, according to the extent of rotation of said wheel, which, in turn, is dependent upon the extent of movement of the manually operated arm 48 (Figure 1), as will later on appear. Contact 108 and contact sector 103 on arm 102 are connected by wire 124, for a purpose which will be

stated later on. Ratchet wheel 101 is rotated by means of a pawl 125 pivotally mounted on the armature 126 of a magnet 127 and held in yielding engagement with the teeth 5 of wheel 101 by a spring 128.

In the case of the group 100 of switch mechanism the wires 109, 110, 111 connect the contacts 106, 107, 108 on arm 102 of that group with the first series of contacts 112, 10 113, 114 leading into that group from station 1; in the case of the group 200 the wires 209, 210, 211 connect the contacts 206, 207, 208 on arm 202 of that group with the second series of contacts 218, 219, 220 leading 15 into that group from station 2, and in the case of the group 300 the wires 309, 310, 311 connect the contacts 306, 307, 308 on arm 302 of that group with the third series of contacts 318, 319, 320 leading 20 into that group from station 3. Otherwise the circuits are the same in all three groups.

From the detailed description thus far given with particular reference to group 25 100 it will be apparent that on each energization of magnet 127, wheel 101 will be moved one step or tooth, its first movement bringing the contacts 106, 107, 108 of arm 67 into engagement with contacts 112, 113, 114, its second movement bringing said contacts into engagement with contacts 118, 119, 120, and its third movement bringing said contacts into engagement with contacts 121, 122, 123. The wheel 101 is held 30 in the position to which the driving pawl 125 rotates it by a spring-pressed retaining pawl 129 which engages the teeth of wheel 101.

Pawls 125, 129 are provided with laterally projecting pins 130, 131 adapted to be 40 engaged by a T-lever 132 and to be disengaged thereby from the teeth of wheel 101. This T-lever 132 is pivotally connected with the armature 133 of a magnet 134, so that when said magnet is energized the T-lever 45 is moved downwardly and, engaging the pins 130, 131, withdraws the pawls 125, 129 from engagement with the wheel 101. Spring 105 is then free to move the wheel 101 and arm 102 in a counter-clockwise 50 direction out of engagement (see wheels 201, 202) with such of the three sets of stationary contacts 112 et seq., 118 et seq., or 121 et seq., as it may be engaged with. In this 55 position of arm 102 the sector contact 103 thereof is disengaged from the contact plate 104.

The energization and deenergization of magnet 127, to effect the movement of the driving pawl 125, and the energization and 60 deenergization of magnet 134, to effect the downward movement of the T-arm 132, are accomplished through circuits and electrical devices included therein which will now be described.

It should be noted here that magnet 134

(and this is true of magnets 234, 334) is of a slow acting type, its windings being short circuited, as shown at 70, so that it is energized only when arm 102 comes to rest over a set of contacts and is not energized while said arm is passing over contacts.

Assuming that the operator at station 1 desires to connect the transmitter thereof with the receiver of station 3, he will first move the arm 48 (Figure 1) from the position in which it is shown to position "3" on the indicator above it. As arm 48, and with it the wheel 44, is so moved, break arm 41 will be moved to the left and its contact 40 engaged with contact 55, thus closing the 80 following circuits: negative pole of battery A, wires 59, 60, armature 61 of relay G, lower contact 62 thereof, wires 63, 64, winding of relay E, wires 65, 66, contact 55, contact 40, left main line wire 42 (Figure 1) 85 left main line wire 135, winding of a polarized relay 136, wires 137, 138, 139, 140 to earth at 141 and thence from earth at 4 by wires 7, 6, 5 to the neutral of battery A. Relay 136, thus energized, will move its armature 142 in a counter-clockwise direction 90 into engagement with a contact 143, thus closing the following circuit from the negative pole of a local battery 144 (Figure 2): wires 145, 139, 146, 147, 148, 149, winding of magnet 134, wires 150, 151, armature 142, contact 143 and wires 152, 153 to the positive pole of battery 144. The circuit thus closed will energize magnet 134, which will then attract its armature 133, thereby 100 moving the T-arm 132 downwardly so that it will, by engagement with the pins 130, 131 thereof, disengage the pawls 125, 129 from the ratchet wheel 101, the spring 105 thereof then moving the ratchet wheel 101 and its arm 102 in a counter-clockwise 105 direction to the position in which they are shown in Figure 2, if at the time they are in an advanced position. Means are provided, which will presently be described, for "clearing" the switch mechanism of Figure 2 when one station finishes telautographic communication with another, such means being controlled by a switch mechanism at the sending station 110 which is operated by the transmitting tracer.

The operator at station 1 will then release arm 48 which, with wheel 44, will then be moved in a counter-clockwise direction by 120 spring 50, the retaining pawl 47 rising and falling with the teeth which pass it and as so moved making and breaking engagement between its tail piece 56 and contact 57 for a purpose which will presently appear. As 125 the arm 48 starts on this counter clockwise or retrograde movement the break arm 41 will be swung to the right thus disengaging its contact 40 from contact 55 and breaking the circuit just described through relay 136 130

from the negative side of battery A, and including left main line wires 42, 135. Relay 136 will then release its armature 142 and break the local circuit just described from the negative of battery 144 through magnet 134, which will then release its armature 133, permitting the spring 154 thereof to raise it and in doing so move the T-arm 132 upwardly out of engagement with the pins 130, 131 of pawls 125, 129 which will then be moved by their springs into engagement with the teeth of ratchet wheel 101.

As the pawl 47 rides over the teeth of wheel 44 passing over it, its tail piece 56 will make and break engagement with contact 57 on the passage of each tooth of the wheel. As, on the retrograde movement of wheel 44 and arm 48 from position "3" on the indicator above them, three teeth will thus move pawl 47 its tail piece 56 will make and break such engagement three times and make and break the following circuit a like number of times: negative of battery A, wires 59, 60, armature 61 of relay G, contact 62, wires 63, 64, winding of relay E, wires 65, 67, contact 57, tail piece 56 of pawl 47, wires 68, 29, winding of relay F, right main line wire 31 (Figure 1), wires 155, 156, winding of a polarized relay 157 and wires 158, 159, 146, 139, 140 to earth at 141 and thence by ground at 4 and wires 7, 6, 5 to the neutral of battery 4.

The current passing through relay 157 over this circuit will cause said relay to rock its armature 160 in a counter-clockwise direction so as to disengage an upper contact piece 161 carried thereby from an upper contact 162, engage contact 161 with an upper-contact 163 and disengage a lower contact 164 carried by armature 160 from a lower contact 165, said contacts 161, 164 being suitably insulated from armature 160. Armature 160 will remain in this position until, as later on described, current of opposite polarity (namely, from the positive of battery A) traverses relay 157, when armature 160 will return to the position in which it is shown. Armature 160, when its contact engages contact 163, closes the following circuit around the winding of relay 157 and including the winding of the magnet 127 which operates the driving pawl 125 of ratchet wheel 101: contacts 161, 163, wire 166, winding of magnet 127, wires 167, 168, 147, 159, 158. Each impulse traversing this circuit from the negative of battery A, will energize magnet 127 which, attracting its armature 126, will cause the driving pawl 125 to rotate wheel 101 one tooth and as, in the described operation of wheel 44, three teeth pass the pawl 47, the circuit through relay 157 and through magnet 134 will be closed and opened three times, with the result that wheel 101 will be rotated three teeth or steps and the arm 102 carried

thereby moved from the position in which it is shown in Figure 2, to an advanced position, with its contacts 106, 107, 108, over contacts 121, 122, 123, in which position it is retained by the retaining pawl 129. Contacts 161, 164 are, as shown, suitably insulated from armature 160.

In this position of the arm 102 the transmitter of station 1 is connected with the receiver of station 3, except for the closing, by the operator, of the master switch 11 at the transmitter of the former and, through it, of the right and left main line circuits from said transmitter to said receiver.

When contact lever 19 of the master switch D is depressed to so connect the transmitter and the receiver the writing currents traversing the main line circuits from the former to the latter are from the positive of battery A. The first effect of such current traversing the left main line is to restore armature 160 to the position in which it is shown in Figure 2. The main line circuits therein established are as follows:

Right line writing circuit,—positive pole of battery A, wire 23, armature 22 of relay E, contact 21, wire 20, master switch contact lever 19, contact 18, wires 17, 15, rheostat 8, pencil arm 10, wires 24, 25, contact 26, contact plate 27 of the master switch, wires 28, 31, (Figure 1) wires 155, 169, contacts 161, 162 of relay 157, wires 170, 115, stationary contact 112, wire 109, contact 106 on arm 102, stationary contact 121, wires 171, 172, contacts 362, 361 of relay 357, wires 369, 355 (Figure 2), wire 31^b, winding of relay F^b, and wires 29^b, 30^b through the receiver C^b of station 3 to ground at 69^b (Figure 3). The right side of local receiver C of station 1 is also connected with the right main line from wire 28 through winding of relay F and wires 29, 30.

Left line writing circuit,—positive of battery A, wire 23, armature 22 of relay E, contact 21, wire 20, contact plate 19, contact plate 18, wires 17, 16, rheostat 9, pen arm 11, wire 32, contact plates 33, 34, wires 35, 37, winding of relay G, wire 38, contact 39, contact 40 of break arm 41, wire 42 (Figure 1), wires 135, 173, lower contacts 164, 165 of relay 157, wires 174, 116, contact 113, wire 110, contact 107 on arm 102, contact 122, wires 175, 176, lower contacts 365, 364 of relay 357, wires 373, 335 (Figure 2), wire 42^b, contact 40^b of arm 41^b, contact 39^b, wire 38^b, winding of relay G^b and wires 37^b, 36^b to the left side of receiver C^b (Figure 3), and to ground at 69^b. The left side of the local receiver of station 1 is also connected with the transmitter of that station on the closing of master switch D, by wire 36 from wire 35.

With the two main line circuits closed as described between the transmitter of sta-

tion 1 and receiver of station 3 telautographic communication from the former to the latter may be carried on in the usual way.

6 If the operator at station 1 after finishing with station 3 and opening master switch D to disconnect the two, should desire to connect his transmitter with the receiver of station 2, he will first open master switch D and then "hang-up" the tracer 43 in a clip 70. This clears the line from station 1 to station 3 through switch group 100, 300, by the following means: Clip 70 is mounted on a spring contact plate 71 which, when

15 tracer 43 is inserted in the clip, engages momentarily a contact 72 thus closing the following circuit over the left line: negative of battery A, wires 59, 73, contact 72, contact plate 71, wire 74, contact 75, armature 76 of relay F, wires 77, 42 (Figure 1) wire 135, winding of relay 136, and wires 137, 138, 139, 140 to ground at 141 (Figure 2) and thence by ground at 4 and wires 7, 6, 5 to the neutral of battery A (Figure 1).

20 Relay 136 thus energized, attracts its armature 142 and closes the circuit heretofore described from the negative of local battery through magnet 134, namely, wires 145, 139, 146, 147, 149, magnet 134, wires 150, 151, 30 armature 142, contact 143 and wires 152, 153 to the positive of battery 144. Relay 134 will thus through its armature 133 pull T-arm 132 downwardly and release pawls 125, 129 from wheel 101, which, with its arm 102,

35 will then be re-set to zero or normal position by its spring 105. Relay F is, as before stated, in the right main line, so that when no current is on this line, its armature 76 rests against contact 75 but when current is 40 on the right line, either in switching or writing, armature 76 is disengaged from contact 75. In the former position of armature 76 clip 70 may be operated to clear the switch mechanism of Figure 2. In the latter position, it cannot be, because the line from the negative of battery A is broken at 75, 76.

The reason for having the circuit just described controlled by relay F is to render clip 70 and contact 72 inoperative for the purpose of closing it and thus clearing the line while the operator at station 1 is selecting another station. During such selection the current traversing the right main line from the negative of battery A will cause 55 relay F to disengage its armature 76 from contact 77 so that even if the tracer 43 be engaged with clip 70 and move contact 71 into engagement with contact 72 the circuit will not be closed.

60 After clearing the line (which is or should be done after each writing operation) the operator at station 1, desiring to connect with the receiver of station 2, will move arm 48 in a clockwise direction to the "2" point 65 in the indicator above it. This will result

in the closing of the circuit before described from the negative of battery A through polarized relay 136, because of the engagement of contact 40 on arm 41 with stationary contact 55. Relay 136 then attracting its armature 142 closes the circuit before described from the negative of local battery 144 through magnet 134. Armature 133 thereof will then pull T-arm 132 down and said arm engaging the pins 130, 131 thereof, will withdraw the driving and retaining pawls 125, 129 from engagement with ratchet wheel 101. Spring 105 will then move wheel 101 and its arm 102 in a counter clockwise direction to normal position, namely, that in which they are shown in Figure 2 if the switch mechanism has not been previously cleared by depression of spring contact 71. The group of switch mechanism 100 of station 1 is thereby reset for operation. The operator at station 1 then releases arm 48 and the spring 50 moves it and wheel 44 in a counter clockwise direction. On this movement of wheel 44, pawl 47 is actuated twice and thereby closes, at contacts 56, 57, (Figure 1) the circuit before described from the negative of battery A through polarized relay 157 and sends two impulses through magnet 127 over the circuit before described as bridged around relay 157, namely, contacts 161, 163, wire 166, winding of magnet 127, and wires 167, 168, 147, 159, 158. Magnet 127 will then twice actuate pawl 125 and thereby rotate ratchet wheel 101 a distance equal to two teeth, with the contacts 106, 107, 108 on arm 102, over stationary contacts 118, 119, 120, wheel 101 and its arm 102 being retained in this position by their retaining pawl 129. In this position of arm 101 the following will be the right and left main line writing circuits to the receiver of station 2; it being understood that armature 160 of relay 157 is in the position shown because of the current then traversing the left main line.

Right line writing circuit: positive pole of battery A, wire 23, armature 22 of relay E, contact 21, wire 20, contact lever 19, contact 18, wires 17, 15, rheostat 8, pencil arm 10, wires 24, 25, contact 26, contact plate 27, wires 28, 31 (Figure 1), wires 155, 169, contacts 162, 161 of relay 157, wires 170, 115, contact 112, wire 109, contact 106 on arm 102, contact 118, wires 177, 178, contacts 262, 261 of relay 257, wires 269, 255 (Figure 2), wire 31^a, winding of relay F^a and wires 29^a, 30^a to the receiver C^a of station 2, and ground at 69^a (Figure 3).

Left line writing circuit: positive of battery A, wire 23, armature 22 of relay E, contact 21, wire 20, contact plate 19, contact plate 18, wires 17, 16, rheostat 9, pencil arm 11, wire 32, contact plates 33, 34, wires 35, 37, winding of relay G, wire 38, contact 39, contact 40 of break arm 41, wire 42 (Figure 130)

- 1) wires 135, 173, lower contacts 164, 165 of relay 157, wires 174, 116, contact 113, wire 110, contact 107 on arm 102, stationary contact 119, wires 179, 180, contacts 265, 264 of relay 257, wires 273, 235, (Figure 2), wire 42^a, contacts 40^a, 39^a, wire 38^a, winding of relay G^a and wires 37^a, 36^a to the left hand side of the receiver C^a and ground at 69^a (Figure 3).
- 10 After finishing telautographic communication between the transmitter of station 1 and the receiver of station 2 the operator at the former station will operate the master switch D so as to disconnect from the receiver of station 2. He will also, in order to "clear" the line, then hang up the tracer 43 in clip 70, thus re-setting the switch mechanism 100, as before described.
- The transmitter of station 2 (Figure 3) may be connected with the receiver of station 1 by moving the arm 48^a of station 2 to the numeral 1 on the indicator above it. This movement of the arm will cause the contact 40^a on the arm 41^a to engage the stationary contact 55^a, thereby closing the following circuit: negative of battery A^a, wires 59^a, 60^a, armature 61^a of relay G^a, contact 62^a, wires 63^a, 64^a, winding of relay E^a, wires 65^a, 66^a, contacts 55^a, 40^a, wire 42^a (Figure 3) wire 235, winding of polarized relay 236, wires 237, 238, 138, 139, 140 to ground at 141 (Figure 2) and thence by ground at 4^a and wires 7, 6, 5 to the neutral of battery A^a (Figure 3). The current traversing this circuit will energize relay 236 so as to move its armature 242 into engagement with contact 243, thus closing the following circuit from local battery 144 (Figure 2): wire 145 from the negative of said battery, wires 139, 146, 147, 148, 248, 249, winding of magnet 234, wires 250, 251, armature 242, contact 243, wires 252, 253, 181, 153 to the positive of battery 144. The resulting energization of magnet 234 will cause it to attract its armature 233 which in turn will draw the T-arm 232 downwardly so that it will, by engagement with the pins 230, 231 thereof, disengage the driving and retaining pawls 225, 229 from the ratchet wheel 201, so that the spring 205 thereof will move the ratchet wheel 201 and its arm 202 in a counter-clockwise direction to normal position, if at the time of the energization of relay 236 they are in an advanced position.
- The operator at station 2 (Figure 3), then releasing arm 48^a, contact 40^a of arm 41^a will be disengaged from contact 55^a, thus breaking the circuit just described, so that the armature 233 and T-arm 232 will be moved upwardly by the spring 254 of said armature. When the arm 48^a, thus released, is moved by its spring 50^a to retracted position one tooth of wheel 44^a will actuate pawl 47^a so that the tail 56^a thereof will engage contact 57^a and close the following circuit through relay 257: negative of battery A^a, wires 59^a, 60^a, armature 61^a of relay G^a, contact 62^a, wires 63^a, 64^a, winding of relay E^a, wires 65^a, 67^a, contact 57^a, tail piece 56^a of pawl 47^a, wires 68^a, 29^a, winding of relay F^a, wire 31^a (Figure 3), wires 255, 256, winding of relay 257, wires 258, 259, 182, 159, 146, 139, 140 to earth at 141 (Figure 2) and thence by ground at 4^a and wires 7^a, 6^a, 5^a, to the neutral of battery A^a (Figure 3). The current traversing this circuit will energize relay 257 which will move its armature 260 in a counter-clockwise direction so that it will engage contacts 261, 263, thus closing the following circuit around the winding of relay 257: contacts 261, 263, wire 266, winding of magnet 227, wires 267, 283, 168, 147, 159, 182, 259, 258. Current traversing this circuit will energize magnet 227 so that the driving pawl 225 will actuate the wheel 201 one tooth, thus bringing arm 202 thereof into line with the first group of stationary contacts 212, 213, 214 of group 200 (Figure 2). With the arm 202 in this position the following will be the main line or writing circuits from the transmitter of station 2 to the receiver of station 1 when the operator at the former closes the master switch D^a, the first effect of this, as before stated, being to send an impulse of positive polarity from battery A^a through relay 257 the armature 260 of which will then be moved clockwise.
- Right line writing circuit; positive pole of battery A^a, wire 23^a, armature 22^a of relay E^a, contact wire 21^a, wire 20^a, master switch plate 19^a, contact plate 18^a, wires 17^a, 15^a, rheostat 8^a, pen arm 10^a, wires 24^a, 25^a, contact 26^a, contact plate 27^a, wires 28^a, 31^a (Figure 3), wires 255, 269, contacts 261, 262 of relay 257, wires 178, 278, 277, contact 218, wire 209, contact 206 on arm 202, contact 212, wires 215, 270, 170, contacts 162, 161 of relay 157, wires 169, 155 (Figure 2), wire 31, winding of relay F and wires 29, 30 to the right hand side of the receiver C of Figure 1 and to ground at 69.
- Left line writing circuit; positive pole of battery A^a, wire 23^a, armature 22^a of relay E^a, contact 21^a, wire 20^a, master switch plate 19^a, contact plate 18^a, wires 17^a, 16^a, rheostat 9^a, pen arm 11^a, wire 32^a, contact plates 33^a, 34^a, wires 35^a, 37^a, winding of relay G^a, wire 38^a, contact 39^a, contact 40^a of break arm 41^a, wire 42^a (Figure 3), wires 235, 273, contacts 264, 265 of relay 257, wires 180, 280, 279, contact 219, wire 210, contact 207 on arm 202, contact 213, wires 216, 274, 174, lower contacts 165, 164 of relay 157, wires 173, 135 (Figure 2), wire 42, contacts 40, 39, wire 38, winding of relay G^a, wires 37, 36 to the left hand side of the receiver C of station 1, and to ground at 69.
- If the operator at station 3 should desire

to connect with station 2 (that station not being "busy" at the time) he will move arm 48^b to "2" on the indicator above it thereby closing the following circuit at contacts 40^b, 55^b, through relay 336 (Figure 2): negative of battery A^b, wires 59^b, 60^b, armature 61^b of relay G^b, contact 62^b, wires 63^b, 64^b, winding of relay E^b, wires 65^b, 66^b, contacts 55^b, 40^b, wire 42^b (Figure 4), wire 335, winding 10 of polarized relay 336, and wires 337, 338, 238, 138, 139, 140 to ground at 141 (Figure 2) and thence by ground at 4^b and wires 7^b, 6^b, 5^b to the neutral of battery A^b. The resulting energization of relay 336 moves armature 342 thereof in a counter-clockwise direction into engagement with contact 343, thereby closing the following circuit through relay 334 from local battery 144 (Figure 3): negative pole of said battery, 20 wires 145, 139, 146, 147, 148, 248, 348, 349, winding of relay 334, wires 350, 351, armature 342, contact 343 and wires 352, 353, 281, 253, 181, 153 to positive of battery 144. Relay 334 will then, through its armature 333, 25 pull T-arm 332 downwardly and, through its engagement with the pins 330, 331 of pawls 325, 329, disengage said pawls from wheel 301 so that the spring 305 may return said wheel and its arm 302 to normal position if at the time they are in an advanced position.

Arm 48^b at station 3 (Figure 4) being then released by the operator it will be retracted or moved in a counter-clockwise direction 35 and its pawl 46^b will move ratchet wheel 49^b in the same direction; break arm 41^b also moving away from contact 55^b and engaging its contact 40^b with stationary contact 39^b. This movement of wheel 49^b will result in 40 two actuations of pawl 47^b and through the contact 36^b thereof the closing (twice) of the following circuit and the sending of two impulses over it through relay 357: negative of battery A^b, wires 59^b, 60^b, armature 61^b of relay G^b, contact 62^b, wires 63^b, 64^b, winding of relay E^b, wires 65^b, 67^b, contact 57^b, tail piece 56^b of pawl 47^b, wires 68^b, 29^b, winding of relay F^b, wire 31^b (Figure 4), wires 355, 356, winding of relay 357, 50 wires 358, 359, 282, 259, 182, 159, 146, 139, 140 to ground at 141 (Figure 2) and thence by ground at 4^b and wires 7^b, 6^b, 5^b to the neutral of battery A^b. On the first of the two impulses traversing this circuit, relay 357 55 will move its armature 360 in a counter-clockwise direction so that the upper contact 361 carried thereby will engage the upper stationary contact 363. On such engagement of said contacts the winding of magnet 327 will be bridged around the winding of relay 357 by the following circuit: contacts 361, 363, wire 366, winding of magnet 327, wires 367, 368, 268, 168, 147, 159, 182, 259, 282, 359, 358. The two impulses traversing the circuit thus closed by armature

360 will cause magnet 327 to twice attract its armature 326 and through it and pawl 325 rotate wheel 301 two teeth, thus moving the arm 302 into line with the second group of contacts 318, 319, 320. 70

Master switch D^b (Figure 4) being then closed by the operator at station 3, the following main line or writing circuit will be closed from the transmitter of station 3 to the receiver of station 2; armature 360 of 75 relay 357 being moved clockwise by the current passing through relay 357 from battery A^b.

Right line, positive of battery A^b, wire 23^b, armature 22^b of relay E^b, contact 21^b, 80 wire 20^b, master switch plate 19^b, contact plate 18^b, wires 17^b, 15^b, rheostat 8^b, pencil arm 10^b, wires 24^b, 25^b, contact 26^b, contact plate 27^b, wires 28^b, 31^b (Figure 4), wires 355, 369, upper contacts 361, 362 of relay 85 357, wires 172, 272, 372, 371, stationary contact 321, wire 309, contact 306 on arm 302, contact 318, wires 377, 378, 278, 178, upper contacts 262, 261 of relay 257, wires 269, 255 (Figure 2), wire 31^a, winding of relay F^a 90 and wires 29^a, 30^a to the right hand side of receiver C^a (Figure 3) and to ground at 69^a.

Left line, positive of battery A^b, wire 23^b, armature 22^b of relay E^b, contact 21^b, wire 20^b, master switch plate 19^b, contact plate 95 18^b, wires 17^b, 16^b, rheostat 9^b, pen arm 11^b, wire 32^b, contact plates 33^b, 34^b, wires 35^b, 37^b, winding of relay G^b, wire 38^b, contact 39^b, contact 40^b of arm 41^b, wire 42^b (Figure 4), wires 335, 373, lower contacts 364, 100 365 of relay 357, wires 176, 276, 376, 375, stationary contact 322, wire 310, contact 307 on arm 302, stationary contact 319, wires 379, 380, 280, 180, lower contacts 265, 264 of relay 257, wires 273, 235 (Figure 2), wire 105 42^a, contact 40^a of arm 41^a, contact 39^a, winding of relay G^a, wires 37^a, 36^a to the left hand side of the receiver C^a of station 2 (Figure 3) and to ground at 69^a.

The connection of station 2 with station 110 3 and of station 3 with station 1, is not described in detail here. This will be readily understood from the description of the method of connecting the other stations with each other, the operation being the same except for slight differences, (Figure 2) in the circuits used for different stations.

It is necessary while two stations are connected for writing from one to the other, or in other words busy, first, that no other station should be permitted to break in, and, second, that the operator attempting to connect with a busy station should know why he fails to connect with it. Means are provided for these purposes and will now be 120 described. For the purpose of such description it will be assumed, for convenience, that the transmitter of station 1 is connected or "busy" with the receiver of station 2, although it will be understood that what takes 125

place, on an attempt to break in, will also take place in the case of any other two connected stations.

If, while stations 1 and 2 are so connected, 5 the operator at station 3 for example, should attempt to connect with station 2, he will move the arm 48^b in a clockwise direction to "2" on the indicator above it and then release the same so that its spring 50^b 10 will move it, and through its pawl 46^b the ratchet wheel 44^b in a counter-clockwise direction. The effect of such clockwise movement is to close the circuit before described 15 (controlled by contacts 40^b, 55^b) from the negative of battery A^b through relay 336 and the local circuit before described (controlled by armature 342 and contact 343) from battery 144 through magnet 334, with the result that T-arm 332 will be pulled 20 down by the armature 333 thereof, the pawls 325, 329 will be disengaged from ratchet wheel 301, and the latter and its arm 302 returned to normal position if at the time they are in an advanced position. The effect 25 of the counter-clockwise movement of arm 48^b and ratchet wheel 44^b is, first, to break this circuit, so that T-arm 332 will move upwardly, thus restoring pawls 325, 329 to engagement with ratchet wheel 301, and second (through the actuation of pawl 47^b by 30 two teeth of wheel 44^b) to engage contact tail piece 56^b of pawl 47^b twice with contact 57^b and send two impulses over the circuit before described (controlled by said contacts 35 56^b, 57^b) through relay 357 and through the circuit before described (controlled by armature 360) bridged around the winding of said relay and including magnet 327, with the result that pawl 325 will turn ratchet wheel 301 and its arm 302 a distance equal 40 to two teeth of the former. The arm 302 will therefore take up a position in line with the second series of contacts 318, 319, 320 in group 300, and will be retained in that 45 position by pawl 329 engaging wheel 301. In this position of arm 302, however, under these conditions, the following circuit is established through relay 336, causing magnet 334 to again attract its armature 333 and 50 pull T-arm 332 down, thus withdrawing pawls 325, 329 from engagement with ratchet wheel 301 so that the latter cannot be operated by magnet 327: positive of battery 144, wires 153, 181, 253, 281, 353, 381, 372, 55 contact 373, middle swinger contact 385 carried by armature 360 of relay 357 (said armature having been moved counter-clockwise from the position shown in Figure 2) wires 386, 387, winding of a relay 388, wire 60 389, spring contact 304, sector contact 303, wire 324 and contact 308 on arm 302, stationary contact 320, wires 392, 292, 279, contact 220, wire 211, contact 208, wire 224 and sector contact 203 on arm 202, spring 65 contact 204, wire 269, winding of relay 288,

wires 287, 286, middle contact swinger 285 of armature 260 of relay 257, contact 284, wires 283, 282, 259, 182, 159, 146, 139, 145 to the negative of battery 144. The closing 70 of this circuit and consequent energization of relays 388, 288 causes the armatures 392, 292 thereof to engage contacts 393, 293 respectively, such engagement between armature 392 and contact 393 closing the following circuit through relay 344: positive of 75 battery 144, wires 153, 181, 253, 281, 353, 381, 372, contact 373, swinger contact 385 carried by armature 360 of relay 357, wires 386, 394, contact 393, armature 392 of relay 388, wires 395, 350, winding of magnet 334, 80 wires 349, 348, 248, 148, 147, 146, 139, 145 to the negative of battery 144. Magnet 234 is not affected through the engagement of armature and contacts 292, 293 of relay 288, 85 by the current traversing the circuit just described for the reason that its connection with the positive of battery 144 is broken at the contacts 273, 285 of relay 257 which, unlike contacts 373, 385, of relay 357, are 90 out of engagement. The latter contacts are 95 operated by current from the negative of battery A^b of station 3, so that its armature 360 has been moved in a counter-clockwise direction.

The effect of the closing of this circuit through the winding of relay 334 is to cause it to attract its armature 333 which, in turn, will again pull down T-lever 332, with the result that pawls 325, 329 are disengaged 100 from ratchet wheel 301 and the latter, with its arm 302, is returned to normal position, so that the main or writing lines from the transmitter of station 3 to the receiver of station 2 are open at the selector switch 105 mechanism.

The operator at station 3, however, does not know this and, therefore, assuming that the connection is made from station 3 to station 2, he will close his master switch D^b 110 but on doing this he will be apprised through the following means that the connection is not made:

Each of stations 1, 2, 3 is equipped with a buzzer magnet I, I^a, I^b, respectively, included in a circuit from the negative of batteries A, A^a, A^b controlled by the relay G, G^a, G^b, respectively, and also by the contact arm 19, 19^a, 19^b, of the master switches D, D^a, D^b. The relays G, G^a, G^b, are included in the left main line circuits from the positive of batteries A, A^a, A^b, but not in the selecting circuits before described from the negative of said batteries. Therefore, except when writing current traverses the 115 left line, their armatures 61, 61^a, 61^b will occupy the positions in which they are shown, namely, resting upon their lower contacts 62, 62^a, 62^b. In this position of these armatures and the raised position shown of the 120 125 130 135 140 145 150 155 160 165 170 175 180 185 190 195 200 205 210 215 220 225 230 235 240 245 250 255 260 265 270 275 master switch contact arms 19, 19^a, 19^b, circuits including buzzer magnets I, I^a, I^b are open and these buzzer magnets are deenergized. They may be closed by depressing 5 the arms 19, 19^a, 19^b. When writing current traverses the left main line relays G, G^a, G^b, their armatures are disengaged from lower contacts 62, 62^a, 62^b so that these circuits will be opened there and cannot be closed 10 by depression of contact arms 19, 19^a, 19^b.

Now, assuming, as before, that station 1 is connected with station 2, and that the operator at station 3 tried to connect with station 2. He does not succeed in doing so 15 because the main line circuit is open at the selector switch mechanism, as just described, but, not knowing this, he depresses contact arm 19^b of master switch D^b. He is then apprised of the fact because the armature 20 61^b of relay G^b rests against lower contact 62^b, so that the depression of arm 19^b closes the following circuit through buzzer magnet I^b and causes it to buzz: negative of battery A^b, wires 59^b, 60^b, armature 61^b, lower contact 62^b of relay G^b, wires 63^b, 78^b, winding 25 of buzzer magnet I^b, armature 79^b thereof, contact 80^b, wire 81^b, contact 82^b, contact plate 19^b, wires 20^b, 21^b, armature 22^b of relay E^b and wire 23^b to the positive of battery A^b. The resulting buzzing of the armature 79^b of magnet I^b will indicate to the operator at station 3 that his station is not connected with station 2. If it were the 30 buzzer would not ring because the circuit including it would be open at 61^b, 62^b because of the energization of relay G^b by the writing current traversing the left line.

This description, though directed specifically to station 3 is equally applicable to 40 each of the other stations should an attempt be made by the operator thereof to connect it with a busy station.

Each of the relays G, G^a, G^b also performs the additional function of preventing 45 the operation of the selecting mechanism of its own station while it is connected with another station for writing. It does so because, as just stated, while writing current is traversing the left line between the two 50 stations the armatures 61, 61^a, 61^b, as the case may be, of the two relays are withdrawn from engagement with lower contacts 62, 62^a, 62^b, as the case may be, so that the selecting circuits over the left and right 55 lines from the negative of battery A, A^a, A^b, as the case may be, are opened at these points. For example, if station 1 be connected for writing with station 2 the selecting circuits from one to the other cannot be 60 established by clockwise and counter-clockwise movements of arm 48 or arm 48^a for the reason that relays G, G^b are energized and withdraw their armatures 70, 70^b, 61, 61^a from contacts 62, 62^b, thus opening the 65 selecting circuit from the negative of bat-

teries A, A^a which would otherwise be established by such movements of said arms.

Additional means, controlled by relays G, G^a, G^b, are provided for preventing such selection operation while two stations are connected for writing. These means are the same in all stations and will therefore be described in connection with station 1 (Figure 1). They consist of a lock magnet J, the armature 83 of which is adapted to engage 75 and prevent movement of the arm 48. Magnet J is included in a circuit as follows, controlled by relay G: negative of battery A, wires 59, 60, armature 61 of relay G, upper contact 84 thereof, wires 85, 86, 87, winding 80 of magnet J, and wire 88 to the neutral of battery A. When writing current is on the left main line relay G is energized, its armature engages contact 84, magnet J is energized and attracts its armature 83, 85 which will engage arm 48 and prevent movement thereof. If station 2 or station 3 be connected with station 1 its relay G^a, G^b will also be energized and its arms 48^a, 48^b locked against movement. 90

Telautographic operation of the transmitter of a station, while it is being connected with the receiver of another, is prevented by the relays E, E^a, E^b of such station. The preventing means, controlled by these relays, are the same in all stations and therefore need only be described with reference to one. Selecting Figure 1, it will be noted that the armature 22 of relay E and lower contact 21 form part of the circuit from the positive of battery A over which writing currents pass to the right and left main lines through rheostats 8, 9. In the position in which said armature and contact are shown this circuit may be closed by depression of master switch arm 19. In a selecting operation, however, namely, during the clockwise and counter-clockwise movements of arm 48, the selecting currents traversing the left and right main lines through relays 136, 157, respectively, will energize relay E which, attracting its armature 22, will open this circuit. 100

A further function performed by relays G, G^a, G^b, is that of locking their respective 115 master switch arms 19, 19^a, 19^b against depression when such stations are receiving from another. This is effected by a lock magnet K, included in the following circuit (Figure 1) which is closed when writing current traverses the left line and relay G is energized and moves its armature against upper contact 84: negative of battery A, wires 59, 60, armature 61 of relay G, contact 84, wires 85, 89, lock magnet K, wires 120 90, 91, 5, to the neutral of battery A. Magnet K, energized by the current traversing this circuit, will attract its armature 92 which will hook over the rear end of contact arm 19 and prevent its depression. If, 130

therefore, station 1 be connected with the receiver of station 2 or station 3 the relay G^a , G^b therein will be energized and through a circuit the same as that just described 5 close a circuit through the lock magnet K^a , K^b , as the case may be, and prevent operation of master switch arm 19^a , 19^b , as the case may be.

In addition each station is provided with 10 a signal lamp L , L^a , L^b to indicate to the operator that it is busy receiving from another station. These lamps, with the circuits therefor, are the same in all stations so that a description of one (Figure 1) will 15 suffice. It is included in a circuit closed by armature 92 of magnet K when said armature is moved, as just described, to lock master switch arm 19. This circuit consists of wire 23 from the positive of battery A , 20 armature 22 of relay E , contact 21, wires 20, 93, armature 92 of lock magnet K , contact 95, wire 96, lamp L and wires 97, 91, 5 to the neutral of battery A . This circuit is closed by the armature 61 of relay G when 25 the latter is energized by writing current traversing the left main line and when two stations are connected the two relays there- 30 of (G , G^a , G^b , as the case may be) are energized and this lamp circuit closed so that the operators at both stations are usually informed that they are connected. This serves 35 the double purpose of so notifying the operator at the station for receiving and the operator at the sending station not to omit to "hang-up," by inserting tracer 43, for example, in clip 70 as before described, thus disconnect his station from the other and put it in condition for connection with another station for receiving.

40 What is claimed is:

1. In a telautographic system the combination with a plurality of stations each provided with transmitting and receiving instruments, and writing line circuits between the instruments at the several stations, of a like number of groups of step-by-step electrically-operated co-acting switching mechanism for establishing writing connection between any two stations, manually-controlled 45 circuit-interrupting means at each station controlling the step-by-step operation of the switching mechanism thereof, current supplying circuits at each station independent of the writing line circuits for supplying 50 current to the instruments at said station, and means for preventing writing connection of one station with another while the latter is in writing connection with a third station.

60 2. In a telautographic system the combination with a plurality of stations each provided with transmitting and receiving instruments, and writing line circuits between the instruments at the several stations, of a like number of groups of step-by-step elec-

trically-operated co-acting switching mechanisms for establishing writing connection between any two stations, manually-controlled station-selecting means at each station controlling the step-by-step operation of the 70 switching mechanism thereof, current supplying circuits at each station independent of the writing line circuits for supplying current to the instruments at said stations, and means set into operation by movement 75 of said station-selecting means for preventing writing connection of one station with another while the latter is in writing connection with a third station.

3. In a telautographic system the combination with a plurality of stations each provided with transmitting and receiving instruments, and writing line circuits between the instruments at the several stations, of a like number of groups of step-by-step electrically-operated co-acting switching mechanisms for establishing writing connection between any two stations, manually-controlled 85 circuit-interrupting means at each station controlling the step-by-step operation of the switching mechanism thereof, current supplying circuits at each station independent of the writing line circuits for supplying current to the instruments at said station, means for preventing writing connection of one station with another while the latter is in writing connection with a third station, and a "busy" signal device at each station set into operation when such writing connection thereof is so prevented. 90

4. In a telautographic system the combination with a plurality of stations each provided with transmitting and receiving instruments, and writing line circuits between the instruments at the several stations, of a like number of groups of step-by-step electrically-operated co-acting switching mechanisms for establishing writing connection between any two stations, manually-controlled 105 circuit-interrupting means at each station controlling the step-by-step operation of the switching mechanism thereof, current supplying circuits at each station independent of the writing line circuits for supplying current to the instruments at said station, means for preventing writing connection of one station with another while the latter is in writing connection with a third station, and a "busy" signal device at each station controlled by the master switch 110 thereof and set into operation when such writing connection thereof is so prevented. 115

5. In a telautographic system the combination with a plurality of stations each provided with transmitting and receiving instruments, and writing line circuits between the instruments at the several stations, of a like number of groups of step-by-step electrically-operated co-acting switching mechanisms for establishing writing connection 120

125

130

- between any two stations manually-controlled circuit-interrupting means at each station controlling the step-by-step operation of the switching mechanism thereof, 5 current supplying circuits at each station independent of the writing line circuits for supplying current to the instruments at said station, and means at each station for clearing the line therefrom to the station with 10 which it has been in writing connection.
6. In a telautographic system the combination with a plurality of stations each provided with transmitting and receiving instruments, and writing line circuits between 15 the instruments at the several stations, of a like number of groups of step-by-step electrically-operated co-acting switching mechanisms for establishing writing connection between any two stations, manually-controlled circuit-interrupting means at each station controlling the step-by-step operation of the switching mechanism thereof, current supplying circuits at each station independent of the writing line circuits for supplying current to the instruments at said station, means at each station for clearing the line therefrom to the station with which it has been in writing connection, and means at each station preventing such clearing while it is in writing connection with another station.
7. In a telautographic system the combination with a plurality of stations each provided with transmitting and receiving instruments, and writing line circuits between the instruments at the several stations, of a like number of groups of step-by-step electrically-operated co-acting switching mechanisms for establishing writing connection between any two stations, manually-controlled circuit-interrupting means at each station controlling the step-by-step operation of the switching mechanism thereof, current supplying circuits at each station independent of the writing line circuits for supplying current to the instruments at said station, and means at each station operable by the transmitter tracer thereof for clearing the line therefrom to the station with which it has been in writing connection.
8. In a telautographic system the combination with a plurality of stations each provided with transmitting and receiving instruments, and writing line circuits between the instruments at the several stations, of a like number of groups of step-by-step electrically-operated co-acting switching mechanisms for establishing writing connection between any two stations, manually-controlled circuit-interrupting means at each station controlling the step-by-step operation of the switching mechanism thereof, current supplying circuits at each station independent of the writing line circuits for supplying current to the instruments at said
- station, means at each station operable by the transmitter tracer thereof for clearing the line therefrom to the station with which it has been in writing connection, and means at each station preventing such clearing while it is in writing connection with another station. 70
9. In a telautograph system the combination with a plurality of stations each provided with transmitting and receiving instruments, and writing line circuits between the instruments at the several stations, of a like number of groups of step-by-step electrically co-acting switch mechanisms for establishing writing connection between stations, manually controlled circuit-interrupting means at each station controlling the step-by-step operation of the switching mechanism thereof, current supplying circuits at each station independent of the writing line circuits for supplying current to the instruments at said station, and means operated by currents other than the telautograph writing currents for preventing connection of one station with another while the latter is in writing connection with a third station. 75 80 85 90
10. In a telautograph system the combination with a plurality of stations each provided with transmitting and receiving instruments, and writing line circuits between the instruments at the several stations, of a like number of groups of step-by-step electrically co-acting switch mechanisms for establishing writing connection between stations, manually controlled circuit-interrupting means at each station controlling the step-by-step operation of the switching mechanism thereof, current supplying circuits at each station independent of the writing line circuits for supplying current to the instruments at said station, and means for preventing the admission of telautograph writing currents to the line wires during the operation of the station selecting means. 95 100 105 110
11. In a telautograph system the combination with a plurality of stations each provided with transmitting and receiving instruments, and writing line circuits between the instruments at the several stations, of a like number of groups of step-by-step electrically co-acting switch mechanisms for establishing writing connection between stations, manually controlled circuit-interrupting means at each station controlling the step-by-step operation of the switching mechanism thereof, current supplying circuits at each station independent of the writing line circuits for supplying current to the instruments at said station, and means for preventing the operation of said selecting means at the stations in writing connection while they are so connected. 115 120 125
12. In a telautograph system the combi- 130

nation with a plurality of stations each provided with transmitting and receiving instruments, and writing line circuits between the instruments at the several stations, of a like number of groups of step-by-step electrically co-acting switch mechanisms for establishing writing connection between stations, manually controlled circuit-interrupting means at each station controlling the step-by-step operation of the switching mechanism thereof, current supplying circuits at each station independent of the writing line circuits for supplying current to the instruments at said station, means controlled at the stations for clearing the lines, and means for indicating that the line clearing operation has been performed.

13. In a telautograph system the combination with a plurality of stations each provided with transmitting and receiving instruments, and writing line circuits between the instruments at the several stations, of a like number of groups of step-by-step electrically co-acting switch mechanisms for establishing writing connection between stations, manually controlled circuit-interrupting means at each station controlling the step-by-step operation of the switching mechanism thereof, current supplying circuits at each station independent of the writing line circuits for supplying current to the instruments at said station, and means at each station controlled by the station-selecting means thereof for clearing the lines from a distant station connected with said selecting means prior to the operation of said selecting means.

14. In a telautograph system the combination with a plurality of stations each provided with transmitting and receiving instruments, and writing line circuits between the instruments at the several stations, of a like number of groups of step-by-step electrically co-acting switch mechanisms for establishing writing connection between stations, manually controlled circuit-interrupting means at each station controlling the step-by-step operation of the switching mechanism thereof, current supplying circuits at each station independent of the writing line circuits for supplying current to the instruments at said station, and means at each station for clearing the lines from connection with other stations, said means being rendered ineffective by the action of the telautograph writing currents.

15. In a telautograph system the combination with a plurality of stations each provided with transmitting and receiving instruments, and writing line circuits between the instruments at the several stations, of a like number of groups of step-by-step electrically co-acting switch mechanisms for establishing writing connection between stations, manually controlled circuit-interrupt-

ing means at each station controlling the step-by-step operation of the switching mechanism thereof, current supplying circuits at each station independent of the writing line circuits for supplying current to the instruments at said station, and means for preventing a writing connection of a telautograph transmitter with the line wires during operation of the selecting switch mechanism at the station at which said transmitter is located and during the receipt of a message at said station.

16. In a telautograph system the combination with a plurality of stations each provided with transmitting and receiving instruments, and writing line circuits between the instruments at the several stations, of a like number of groups of step-by-step electrically co-acting switch mechanisms for establishing writing connection between stations, manually controlled circuit-interrupting means at each station controlling the step-by-step operation of the switching mechanism thereof, current supplying circuits at each station independent of the writing line circuits for supplying current to the instruments at said station, means for preventing the operation of the station selecting means while the telautograph writing currents are traversing the line wires, and a signal for indicating that the telautograph instruments are in writing connection.

17. In a telautograph system the combination with a transmitter and receiver and means for connecting them for writing, of a transmitter tracer clip and electrical connections controlled thereby for clearing the lines between the transmitter and receiver after a writing operation.

18. In a telautographic system the combination with a plurality of stations each provided with a transmitter and a receiver, of a like number of groups of electrically-operated co-acting switching mechanisms, main line wires connecting each station with its group of switching mechanism and adapted through the latter and the other switching mechanisms to connect it with the main lines of other stations, manually-controlled station-selecting means at each station, and means controlled thereby for causing currents of reverse polarity to the writing currents to traverse one of the main lines therefrom and through such currents effecting the operation of the switching mechanism thereof.

19. In a telautographic system the combination with a plurality of stations each provided with a transmitter and a receiver, of a like number of groups of electrically-operated co-acting switching mechanisms, main line wires connecting each station with its group of switching mechanism and adapted through the latter and the other

switching mechanisms to connect it with the main lines of other stations, manually-controlled station-selecting means at each station, means controlled thereby for causing currents of reverse polarity to the writing currents to traverse one of the main lines therefrom and through such currents effecting the operation of the switching mechanism thereof, and means controlled by said station-selecting means for causing such reverse currents to traverse another of the main lines and through such currents effecting the return to normal position of the switching mechanism so operated.

18 20. In a telautographic system the combination with a plurality of stations each provided with a transmitter and a receiver, of a like number of groups of electrically-operated co-acting switching mechanisms, main line wires connecting each station with its group of switching mechanism and adapted through the latter and the other switching mechanisms to connect it with the main lines of other stations, manually-controlled station-selecting means at each station, means controlled thereby for causing currents of reverse polarity to the writing currents to traverse one of the main lines therefrom and through such currents effecting the operation of the switching mechanism thereof, and means operable by the transmitter tracer of said station for causing such reverse currents to traverse another of the main lines and through such currents effecting the return to normal position of the switching mechanism so operated.

21. In a telautographic system the combination with a plurality of stations each provided with a transmitter and a receiver, of a like number of groups of electrically-operated co-acting switching mechanisms, main line wires connecting each station with its group of switching mechanism and adapted through the latter and the other switching mechanisms to connect it with the main lines of other stations, manually-controlled station-selecting means at each station for causing currents of reverse polarity to the writing currents to traverse one of the main lines therefrom and through such currents effecting the operation of the switching mechanism thereof, and means for preventing writing connection of one station with another while the latter is in writing connection with a third station.

22. In a telautographic system the combination with a plurality of stations each provided with a transmitter and a receiver, of a like number of groups of electrically-operated co-acting switching mechanisms, main line wires connecting each station with its group of switching mechanism and adapted through the latter and the other switching mechanisms to connect it with the main lines of other stations, manually-

controlled station-selecting means at each station for causing currents of reverse polarity to the writing currents to traverse one of the main lines therefrom and through such currents effecting the operation of the 70 switching mechanism thereof, and means controlled by said station-selecting means for causing such reverse currents to traverse another of the main lines and through such currents effecting the return to normal 75 position of the switching mechanism so operated.

23. In a telautographic system the combination with a plurality of stations each provided with a transmitter and a receiver, of 80 a like number of groups of electrically-operated co-acting switching mechanisms, main line wires connecting each station with its group of switching mechanism and adapted through the latter and the other 85 switching mechanisms to connect it with the main lines of other stations, manually-controlled station-selecting means at each station for causing currents of reverse polarity to the writing currents to traverse one 90 of the main lines therefrom and through such currents effecting the operation of the switching mechanism thereof, and means operable by the transmitter tracer of said station for causing such reverse currents to 95 traverse another of the main lines and through such currents effecting the return to normal position of the switching mechanism so operated.

24. In a telautographic system the combination with a plurality of stations each provided with a transmitter and a receiver, of a like number of groups of electrically-operated co-acting switching mechanisms including step-by-step devices, main line wires 100 connecting each station with its group of switching mechanism and adapted through the step-by-step device thereof and the other switching mechanisms to connect it with the main lines of other stations, and manually-controlled 105 station-selecting means at each station for causing currents of reverse polarity to the writing currents to traverse one of the main lines therefrom and through such currents effecting the operation of the 110 step-by-step device of the switching mechanism thereof.

25. In a telautographic system the combination with a plurality of stations each provided with a transmitter and a receiver, of 115 a like number of groups of electrically-operated co-acting switching mechanisms including step-by-step devices, main line wires connecting each station with its group of switching mechanism and adapted 120 through the step-by-step device thereof and the other switching mechanisms to connect it with the main lines of other stations, manually-controlled station-selecting means at 125 each station for causing currents of reverse 130

polarity to the writing currents to traverse one of the main lines therefrom and through such currents effecting the operation of the step-by-step device of the switching mechanism thereof, and means controlled by said station-selecting means for causing such reverse currents to traverse another of the main lines and through such currents effecting the return to normal position of the switching mechanism so operated.

26. In a telautographic system the combination with a plurality of stations each provided with a transmitter and a receiver, of a like number of groups of electrically-operated co-acting switching mechanisms including step-by-step devices, main line wires connecting each station with its group of switching mechanism and adapted through the step-by-step device thereof and the other switching mechanisms to connect it with the main lines of other stations, manually-controlled station-selecting means at each station for causing currents of reverse polarity to the writing currents to traverse one of the main lines therefrom and through such currents effecting the operation of the step-by-step device of the switching mechanism thereof, and means operable by the transmitter tracer of said station for causing such reverse currents to traverse another of the main lines and through such currents effecting the return to normal position of the switching mechanism so operated.

27. In a telautographic system the combination with a plurality of stations each provided with a transmitter and a receiver, of a like number of groups of electrically-operated co-acting switching mechanisms including step-by-step devices, main line wires connecting each station with its group of switching mechanism and adapted through the step-by-step device thereof and the other switching mechanisms to connect it with the main lines of other stations, manually controlled station-selecting means at each station for causing currents of reverse polarity to the writing currents to traverse one of the main lines therefrom and through such currents effecting the operation of the step-by-step device of the switching mechanism thereof, and means for preventing writing connection of one station with another while the latter is in writing connection with a third station.

28. In a telautographic system the combination with a plurality of stations each provided with a transmitter and a receiver, of a like number of groups of electrically-operated co-acting switching mechanisms including step-by-step devices, main line wires connecting each station with its group of switching mechanism and adapted through the step-by-step device thereof and the other switching mechanisms to connect it with the main lines of other stations, manually-con-

trolled station-selecting means at each station for causing currents of reverse polarity to the writing currents to traverse one of the main lines therefrom and through such currents effecting the operation of the step-by-step device of the switching mechanism thereof, means controlled by said station-selecting means for causing such reverse currents to traverse another of the main lines and through such currents effecting the return to normal position of the switching mechanism so operated, and means for preventing writing connection of one station with another while the latter is in writing connection with a third station.

29. In a telautographic system the combination with a plurality of stations each provided with a transmitter and a receiver, of a like number of groups of electrically-operated co-acting switching mechanisms including step-by-step devices, main line wires connecting each station with its group of switching mechanism and adapted through the step-by-step device thereof and the other switching mechanisms to connect it with the main lines of other stations, manually-controlled station-selecting means at each station for causing currents of reverse polarity to the writing currents to traverse one of the main lines therefrom and through such currents effecting the operation of the step-by-step device of the switching mechanism thereof, means operable by the transmitter tracer of said station for causing such reverse currents to traverse another of the main lines and through such currents effecting the return to normal position of the switching mechanism so operated, and means for preventing writing connection of one station with another while the latter is in writing connection with a third station.

30. In a telautographic system the combination with a plurality of stations each provided with a transmitter and a receiver, of a like number of groups of electrically-operated co-acting switching mechanisms including step-by-step devices, main line wires connecting each station with its group of switching mechanism and adapted through the step-by-step device thereof and the other switching mechanisms to connect it with the main lines of other stations, manually-controlled station-selecting means at each station for causing currents of reverse polarity to the writing currents to traverse one of the main lines therefrom and through such currents effecting the operation of the step-by-step device of the switching mechanism thereof, and means for restoring the step-by-step device thereof to normal position and preventing writing connection of one station with another while the latter is in writing connection with a third station.

31. In a telautographic system the combination with a plurality of stations each pro-

- vided with a transmitter and a receiver, of a like number of groups of electrically-operated co-acting switching mechanism including step-by-step devices, main line wires 5 connecting each station with its group of switching mechanism and adapted through the step-by-step device thereof and the other switching mechanisms to connect it with the main lines of other stations, manually- 10 controlled station-selecting means at each station for causing currents of reverse polarity to the writing currents to traverse one of the main lines therefrom and through such currents effecting the operation of the 15 step-by-step device of the switching mechanism thereof, means controlled by said station-selecting means for causing such reverse currents to traverse another of the main lines and through such currents effecting the 20 return to normal position of the switching mechanism so operated, and means for restoring the step-by-step device thereof to normal position and preventing writing connection of one station with another while the 25 latter is in writing connection with a third station.
32. In a telautographic system the combination with a plurality of stations each provided with a transmitter and a receiver, of a like number of groups of electrically-operated co-acting switching mechanisms including step-by-step devices, main line wires connecting each station with its group of switching mechanism and adapted through 30 the step-by-step device thereof and the other switching mechanisms to connect it with the main lines of other stations, manually-controlled station-selecting means at each station for causing currents of reverse polarity 35 to the writing currents to traverse first one and then another line therefrom, each group of switching mechanism including a relay connected with one main line for effecting the operation of the step-by-step device of said group and another relay for restoring said device to normal position, and means at each station for controlling said last named relay. 40
35. In a telautographic system the combination with a plurality of stations each provided with a transmitter and a receiver, of a like number of groups of electrically-operated co-acting switching mechanisms including step-by-step devices, main line wires connecting each station with its group of switching mechanism and adapted through 45 the step-by-step device thereof and the other switching mechanisms to connect it with the main lines of other stations, manually-controlled station-selecting means at each station for causing currents of reverse polarity 50 to the writing currents to traverse one of the main lines therefrom and through such currents effecting the return to normal position of the switching mechanism so operated, and means 55 tracer of said station for causing such reverse currents to traverse another of the main lines and through such currents effecting the return to normal position of the switching mechanism so operated, and means 60 for restoring the step-by-step device thereof to normal position and preventing writing connection of one station with another while the latter is in writing connection with a third station.
33. In a telautographic system the combination with a plurality of stations each provided with a transmitter and a receiver, of a like number of groups of electrically-operated co-acting switching mechanisms including 65 step-by-step devices, main line wires con-
- necting each station with its group of switching mechanism and adapted through the step-by-step device thereof and the other switching mechanisms to connect it with the main lines of other stations, and manually- 70 controlled station-selecting means at each station for causing currents of reverse polarity to the writing currents to traverse first one and then another main line therefrom and through such currents effecting the 75 operation of the step-by-step device of the switching mechanism thereof. 80
34. In a telautographic system the combination with a plurality of stations each provided with a transmitter and a receiver, of a like number of groups of electrically-operated co-acting switching mechanisms including step-by-step devices, main line wires connecting each station with its group of switching mechanism and adapted through 85 the step-by-step device thereof and the other switching mechanisms to connect it with the main lines of other stations, manually-controlled station-selecting means at each station for causing currents of reverse polarity 90 to the writing currents to traverse first one and then another line therefrom, each group of switching mechanism including a relay connected with one main line for effecting the operation of the step-by-step device of said group and another relay for restoring said device to normal position, and means at each station for controlling said last named relay. 95
35. In a telautographic system the combination with a plurality of stations each provided with a transmitter and a receiver, of a like number of groups of electrically-operated co-acting switching mechanisms including step-by-step devices, main line wires connecting each station with its group of switching mechanism and adapted through 100 the step-by-step device thereof and the other switching mechanisms to connect it with the main lines of other stations, manually-controlled station-selecting means at each station for causing currents of reverse polarity 105 to the writing currents to traverse first one and then another line therefrom, each group of switching mechanism including a relay connected with one main line for effecting the operation of the step-by-step device of said group and another relay for restoring said device to normal position, and means 110 at each station, operable by the transmitter tracer thereof, for controlling said last named relay. 115

In testimony whereof, I have hereunto set my hand.

GEORGE S. TIFFANY.
